KNITTING MACHINE

Henry Harold Holmes and Robert Harold Robinson, Leicester, England, assignors to Wildt and Company Limited, Leicester, England, a British company

Application September 15, 1931, Serial No. 562,898
In Great Britain October 17, 1930

8 Claims. (Cl. 66—134)

This invention consists in improvements in or relating to knitting machines and is applied particularly to improvements in yarn-feeding means for such machines.

5 The invention provides novel means by which the yarn to be newly introduced to the needles is fed to those needles and also a novel means by which the yarn is severed when it is to be withdrawn. The invention is particularly applicable to a machine in which wale-threads are supplied to some or all of the needles and may be used in machines such as are described for instance in prior British Patents Nos. 327,958, 327,-10 987, 327,988, and 328,026.

15 In order that the foregoing and other features of the present invention may be more clearly understood a preferred example will now be described with the aid of the accompanying drawings, in which—

20 Figure 1 is a side elevation on an enlarged scale of a combined yarn-feeder and gripper.

Figure 2 is a plan of the feeder illustrated in Figure 1;

25 Figure 3 is a diagrammatic illustration showing how the ground- and splicing-threads are laid in the needle-hooks.

Figure 4 diagrammatically illustrates the position of the feeder relatively to the needles and the stitch-cam at the moment of introducing a 30 yarn to the needles, and

Figure 5 illustrates similar parts at the moment of withdrawing the yarn and snapping it.

Like reference numerals indicate like parts in the several figures of the drawings.

35 The feeder illustrated in Figures 1 and 2 comprises an upright arm 10 having at its upper end a portion 11 bent over substantially at right angles to project towards the needles, one of which is shown and designated as 12. The yarn delivery eye 13 is formed at the outer extremity of the arm 11 and other yarn-guide eyes 14 and 15 are also provided through which a yarn 16 is threaded in the manner shown in Figure 1.

40 The arm 10 is pivoted in a bracket 17 on a pin 18. The bracket is secured to or may form part of a ring-like support and the yarn-feeder, by 45 rocking about the pivot-pin 18, can move the delivery eye 13 towards and away from the needles. The feeder is shown in full lines in its retracted or non-feeding position and the forward end portion of it is shown in chain-lines in the advance or feeding position.

45 The yarn 16 where it passes from the feed-eye 14 to the eye 13 extends for a short distance along 50 an upper surface of the feeder and is held against

5 that surface by means of a gripper 19. The gripper comprises a jaw-member pivotally mounted at 20 between two arms 21 arranged one on each side of the arm 11 of the feeder. The arms 21 are pivoted at 22 to the arm 11 and extend rearwardly beyond the pivot beneath a spring-plate 23. The gripper-jaw 19 is of arch form and bears, as shown in Figure 1, on the arm 11 on both sides of the pivot 20 when it is held in engagement therewith. The gripper-jaw is normally pressed 10 on to the arm 11 by a light spring 24 coiled at its inner end around a pin 25 mounted in the upright portion 10 of the feeder and having its free end hooked at 26 over the arms 21. The spring 24 holds the forward extremity of the gripper-jaw 19 lightly against the yarn where it extends between the feed-eyes 13 and 14.

55 The lower end of the yarn-guide is formed with a laterally extending portion 27 which can be engaged by a cam 28. Engagement between the latter and the extension 27 moves the feeder into the full-line position illustrated in Figure 1 against the pressure of a spring 29 bearing at one end against the portion 10 of the feeder above the pivot 18 and at the other end housed within 25 a socket 30. The latter is clamped by means of a screw 31 to a stud 32 to the upper end of which the spring plate 23 is secured by bolt 33 and nut 34.

30 Between the cam 28 and the end 27 of the feeder there will be relative movement in the feed direction and in the case of a circular machine the angular extent of the cam 28 will correspond with the angular extent of those needles in the needle-cylinder over which it is desired to dis- 35 continue the feed of the yarn 16. There may be more than one cam 28 disposed at intervals around the axis of the cylinder and the cam or each of them may be mounted for movement into and out from the path of the extension 27. 40

When it is desired to hold the feeder in its full-line or inoperative position for any length of time after it has been moved thereinto by means of the cam 28, a catch 35 is arranged to engage above a shoulder 36 formed on the rear 45 edge of the feeder. The catch is spring-urged towards its locking position by the spring 35 so that immediately the feeder has been retracted by means of the cam 28 it will engage with the shoulder 36 and thus hold the feeder inoperative until an abutment 37 is moved into the path of a tail 38 of the catch 35, the latter constituting one arm of a bellcrank lever of which the tail 38 constitutes the other arm. The abutment 37 50 may be movable into and out from the path of 55

the tail 38 under any preferred form of pattern control.

When the feeder thus described is to be used as a splicing yarn-feeder for introducing a splicing yarn to the required parts of knitted hose and half-hose the feeder will normally be retained in the inoperative position by means of the catch 35 during the knitting of the upper leg and part of the ankle. When the position in 10 the ankle is reached at which the splicing yarn is to be introduced the abutment 37 will be moved into the path of the tail 38 (it being understood that there will be relative rotation about the axis of the machine between these two parts) there- 15 by releasing the catch and permitting the feeder to be advanced rapidly by pressure of the spring 29 into the feeding (chain-line) position. The feeder will thus supply its yarn to the needles until it reaches the cam 28 whereupon it will be 20 withdrawn and will be locked in its withdrawn position by the catch 35. This sequence of operations will be repeated until the splice is completed whereupon the abutment 37 will be moved out of the path of the tail 28. Where the splicing 25 is required to continue for say one-half of the circumference of the article being knitted, it is obvious that members 28 and 37 will be approximately diametrically opposite, considered in relation to the circle of needles.

30 In such a case the cam 28 need be only of small angular extent. Alternatively, the cam may serve to hold the feeder out of operation before the required portion of a knitting course without the aid of the catch such as 35, in which case the angular extent of cam 28 will wholly determine the period of inactivity.

40 The yarn from a previous withdrawal will have been severed close to the last needle to take the yarn so as to leave only a small tail end projecting from the delivery eye 13 of the feeder. As will be seen from the chain-line position of the latter its feeding position is as close to the needle-hooks as is possible having regard to mechanical considerations.

45 Figures 1 and 4 show in chain-lines in Figure 1 and in full-lines in Figure 4 the position at which the delivery eye 13 is presented to the needles at the moment of introducing the yarn to the latter. The delivery eye 13 presents the free trailing end of yarn to a needle which has been partially drawn down by the stitch-cam so that its latch has commenced its closing movement. This is indicated in Figure 1 in the representation of a needle 12 where it will be seen 50 that a previous loop shown in section at 39 has commenced to close the latch. Figure 4 shows the relative positions of the parts at a time momentarily after that represented in Figure 1, and it will be seen from Figure 4 that the previous loop 39 has been moved on its needle 12 by descent of that needle down the stitch-cam 112 to 55 close the latch of the needle. As the lapse of time is only of a momentary extent in the movement of the needle from the position of Figure 1 to that of Figure 4, the latch will be understood to have closed rapidly and in so doing will have whipped the free end of the yarn into the needle hook. It is found that the yarn becomes gripped (provided that the tail end is approximately $\frac{1}{2}$ " long) with accuracy so as to be taken by the 60 first and successive needles and drawn by them into knitted loops.

70 It will be understood that the portion 11 of the feeder in Figure 4 corresponds to the part de- 75 noted by similar reference in Figure 1 and in

Figure 4 the remaining portion and its associated parts are to be understood as included. The movement of the feeder into the position of Figure 4 will effect release of the gripper substantially at the moment that the needle 12 takes 5 the yarn, that is to say, the yarn will be fed to a needle and released thereto only when that needle is approaching the lower end of the stitch-cam as shown in Figure 4 so that its latch has already commenced to close.

10 The cam 28 may be adjustable angularly around the axis of the machine in order to determine the exact moment at which the feeder is to be withdrawn and in order to obtain this angular adjustment the cam is mounted by means 15 of a bolt by which it is received in an elongated slot 49.

Wherever reference is made herein to movements of parts suitable to a circular machine it will be understood that if the feeder is applied 20 to a flat frame machine the equivalent movement is intended.

It is possible to adjust the position of the free end of the spring plate or abutment 23 in the path of the movement of the gripper 19. This 25 may be effected by means of the screw 33 by which the free end of the plate 23 can be retracted from or advanced towards the needle-bed and also in a vertical direction. The purpose of this adjustment is to time the closing of the 30 gripper 19 on to the yarn 16 in the withdrawal stroke of the feeder, and it will be understood that until the gripper 19 has been closed on to the yarn by means of the plate 23 the yarn can run freely in the feeding direction between the 35 jaw and the part 11. Pressure, however, of the end of the plate 23 on the gripper-jaw 19 serves to grip the yarn between the jaw and the part 11 so as to prevent free running of the yarn.

40 The spring plate 23 can be replaced by any other abutment which may be either relatively fixed in relation to the movement of the feeder or may by any preferred means be brought into engagement with the gripper-jaw at the time required.

45 If the yarn is to be severed after it is withdrawn the gripper will be closed on to the yarn at the moment of or just prior to severance thereof.

In order to fulfill another improvement according to the invention the yarn-feeder and its associated yarn-gripper is combined with means to operate as or when the feeder is withdrawn to close the gripper at a time when the needle, which is the last one to take the yarn from the feeder, 50 is approximately at the knocking over point. If this is fulfilled it is found that the thread will be severed with accuracy close to the surface of the fabric. The means to close the feeder is in the example illustrated in Figures 1 and 2 constituted 55 by the spring-plate 23 which, when the feeder is retracted into the full-line position, presses on the gripper-jaw 19 to clamp the yarn between it and the part 11. In accordance with this improvement, however, the movement of the feeder 60 into the position at which the jaw will be closed by the spring-plate 23 is timed so that such a closing of the jaw takes place so that a breaking strain is imposed on the yarn as or immediately after the loop or loops formed in the 65 previous course are being or have been knocked over on the needle which is the last to take the 70 yarn supplied by the feeder.

75 This is diagrammatically illustrated in Figures 3 and 5 in which the splicing yarn 16, which 75

by movement of the feeder has now been withdrawn (as clearly shown in Figure 5) from the feeding position after being taken by the needle 29, is to be understood as having applied to it 5 by means of the gripper a breaking stress just at the moment that the previously formed loop has been knocked over. As seen from Figure 5, the needle 129 has reached a position on the stitch-cam 112 approximately at the bottom of the latter and at this position the previously drawn loop has been knocked over the head of the needle and the new loop has been drawn. At this moment, the yarn 16 is lapped more or less sharply round the bight of the previous loop indicated at 139 and will be snapped off close to the position where it is thus lapped round that loop.

Tests have demonstrated that the reason why the yarn is severed in this fashion is that the 20 yarn is pulled sharply against the previous stitch or stitches much in the way that string can be broken by a sharp pull against a loop or length of string around which the string is turned.

When this system of breaking the yarn is employed no cutter is required and the severing takes place entirely by the pull on the yarn at the time specified above. The invention is particularly suitable for use on fine counts of yarn such, for example, as silk or artificial silk and fine cotton splicing yarns used in the knitting of hosiery and like goods.

It will be appreciated that the slot 40 of cam 28 permits circumferential adjustment of the cam and consequently adjustment can be made as to the moment of withdrawal of the feeder in its passage past the needles. Consequently, the closing of the gripper jaw 19 on to the yarn 16 can be selectively determined to take place in relation to any particular needle at which severance of the yarn is desired. In timing the withdrawal operation of the feeder and closure of the gripper allowance must be made for stretch which will occur in the yarn immediately prior to its severance by snapping. Thus, by a suitable adjustment in a circumferential direction of the position of cam 28 fancy splicing can be produced. In practice it is found that the yarn-feeder can be rapidly withdrawn, and if the spring-plate 23 is disposed with its outer or free end in the position illustrated in Figures 1 to 2 relatively to the feeding and non-feeding positions of the splicing yarn feeder, automatic severance of the yarn will take place leaving practically no free end thereof on the face of the fabric. Thus, 55 the edge of the splice will be clearly demarcated both at the commencement and at the termination of the splice and this improvement avoids a ragged or non-clearly defined demarcation of the line of the splice where the thread is withdrawn. In fact, the line of the splice is a very clean line and is approximately as clearly defined as is the line of commencement thereof.

It is to be understood that the means described herein and illustrated in the drawings for closing the gripper on to the yarn, means for moving the feeder, and the nature of the feeder movement are examples only of any constructions producing a similar result.

In the particular form illustrated, a very rapid removal of the yarn from the feeding position is brought about because as the feeder is swung about its pivot the feeding eye is not only retracted but is also lifted.

Although the combined feeder and yarn-gripper is particularly applicable for use as a splic-

ing yarn-feeder in accordance with the description given above, it is not limited to this particular purpose as it may be employed for feeding other yarns such as ground or patterning yarns.

We claim:—

1. In a knitting machine the combination of a movable yarn-feeder capable of yarn-feeding and withdrawal movements, means for moving said feeder into and out of said feeding position, a yarn-gripper in juxtaposition with said yarn-feeder and movable therewith, an abutment in the path of the gripper to engage and close the gripper at the moment the feeder is withdrawn, and means to adjust the abutment in the path of movement of the gripper to regulate the timing of the engagement between the abutment and the gripper as the feeder is moved.

2. For a knitting machine having a bed of needles and a stitch-cam to actuate said needles, the combination of a yarn-feeder, a yarn-gripper in juxtaposition therewith, to hold a free floating end of yarn extending from the feeder when the latter is in the non-feeding position, and feeder-actuating means timed to move the feeder into the feeding position to present the free end of yarn to a needle only when that needle is approaching the lower end of the stitch-cam and its latch has commenced to close but is not fully closed.

3. For a knitting machine having a bed of needles and a stitch-cam to actuate said needles, the combination of a movable yarn-feeder capable of yarn-feeding and withdrawal movements, a yarn gripper in juxtaposition and movable therewith to hold a free floating end of yarn extending from the feeder when the latter is in the non-feeding position, feeder withdrawal means, an abutment disposed in the path of the gripper to engage and close the latter during withdrawal movement of the feeder into the non-feeding position, means to adjust the position of the abutment in the path of movement of the gripper, and feeder-actuating means timed to move the feeder into the feeding position to present the free end of the yarn to a needle only when that needle is approaching the lower end of the stitch-cam and its latch has commenced to close but is not fully closed.

4. For a yarn knitting machine having a bed of needles and a stitch-cam to actuate said needles, the combination of a movable yarn-feeder capable of yarn-feeding and withdrawal movements, a yarn-gripper associated therewith, feeder withdrawal means and means operating on the withdrawal of the feeder, to close the gripper on to the yarn substantially at the moment that the last needle to take the yarn has reached approximately the bottom of the stitch-cam.

5. For a yarn knitting machine having a bed of needles and a stitch-cam to actuate said needles, the combination of a movable yarn-feeder capable of yarn-feeding and withdrawal movement, a yarn-gripper associated therewith, feeder withdrawal means and means to close the gripper on to the yarn when the last needle to take the yarn has reached the knocking-over point.

6. For a knitting machine, the combination of a movable yarn-feeder capable of yarn-feeding and withdrawal movements, a yarn-gripper in juxtaposition with said feeder and movable therewith, an abutment disposed in the path of the gripper to engage and close the latter during the feeder withdrawal movement, and means to ad-

just the abutment in the path of movement of the gripper, thereby to adjust the timing of the engagement between the abutment and the gripper, relatively to the feeder withdrawal movement.

7. For a knitting machine having a bed of needles and a stitch cam to actuate said needles, the combination of a movable yarn-feeder capable of yarn-feeding and withdrawal movements, a yarn gripper associated therewith and movable at least as the feeder is moved during withdrawal, feeder withdrawal means, means to close the gripper onto the yarn substantially at the moment that the last needle to take the 10
15
yarn has reached approximately the bottom of the stitch cam, an abutment disposed in the path of the gripper to engage with and to serve as the means to close the gripper onto the yarn, and

means to adjust the position of the abutment in the path of movement of the gripper to adjust the timing of closure of the gripper onto the yarn relatively to the feeder movement.

8. For a knitting machine, the combination of a yarn feeder capable of yarn-feeding and withdrawal movements, a yarn gripper mounted upon the yarn feeder to be movable therewith, a gripper-closing abutment disposed in the path of movement of the gripper to operate thereon as 10
the feeder is withdrawn, means to adjust the position of the abutment in the path of movement of the gripper thereby to adjust the timing of engagement between the abutment and the gripper relatively to the feeder movement. 15
